CLAIM

The ornamental design for a watch strap, as shown and described.

DESCRIPTION

FIG. 1 is an isometric view of a watch strap showing the new design;

FIG. 2 is a front view of the invention illustrated in FIG. 1; FIG. 3 is a rear view of the invention illustrated in FIG. 1; FIG. 4 is a left elevation view of the invention illustrated in FIG. 1;

FIG. 5 is a right elevation view of the invention illustrated in FIG. 1;

FIG. 6 is a top view of the invention illustrated in FIG. 1; FIG. 7 is a bottom view of the invention illustrated in FIG. 1;

FIG. 8 is an enlarged elevation view taken in the direction from the gap between the two portions of the watch strap towards the end of the one portion; and,

FIG. 9 is an enlarged elevation view taken in the direction from the end of the one portion towards the gap between the two portions of the watch strap.

The broken lines in the drawing figures indicate portions of the watch strap that form no part of the claimed design.

1 Claim, 6 Drawing Sheets
